UNITED STATES PATENT OFFICE.

GEORGE W. DAUTH, OF READING, PENNSYLVANIA.

DESIGN FOR SHIELDS.

Specification forming part of Design No. 7,148, dated February 3, 1874; application filed January 19, 1874.
[Term of Patent 7 years.]

To all whom it may concern:

Be it known that I, GEORGE W. DAUTH, of Reading, in the county of Berks and State of Pennsylvania, have invented a certain new and useful Design for Armor-Shields; and I do hereby declare that the following is a full, clear, and exact description thereof, reference being had to the accompanying drawings and to the letters of reference marked thereon, which form a part of this specification.

The nature of my invention is fully illustrated in the accompanying drawing, to which reference is made.

I make my armor-shield generally of a piece of sheet metal, of oval form, and bent to form a convex outer surface. This shield is covered on the outside with leather, and the two parts

stitched together, forming an ornamental row of stitches, *a a*, around the entire edge of the shield. The outer surface of the shield has a broad diagonal stripe, *A*, painted white, said stripe taking up about one-third of the area of the shield, more or less. The two remaining parts, *B* and *C*, are painted, respectively, red and blue.

What I claim as my invention is—

A design for a shield, as above described.

In testimony that I claim the foregoing as my own I affix my signature in the presence of two witnesses.

GEORGE W. DAUTH.
